ATTORNEY:

UNITED STATES PATENT OFFICE.

WILLIAM C. CODMAN, OF PROVIDENCE, RHODE ISLAND, ASSIGNOR TO
GORHAM MANUFACTURING COMPANY, OF PROVIDENCE, RHODE
ISLAND, A CORPORATION.

DESIGN FOR A HANDLE OF SPOONS, FORKS, OR SIMILAR ARTICLES.

No. 38,020.

Specification for Design.

Patented May 22, 1906.

Application filed April 12, 1906. Serial No. 311,398. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for the Handles of Spoons, Forks, or Similar Articles, reference being had to the accompanying drawings.

Figure 1 is a view of the obverse side of the

handle, showing my design; and Fig. 2 is a reverse view of the same.

I claim—

The ornamental design for the handle of a spoon, fork or similar article, as shown.

WILLIAM C. CODMAN.
